UNITED STATES PATENT OFFICE.

THOMAS F. O'SHAUGHNESSY, OF NEW YORK, N. Y.

PIANO SOUNDING-BOARD.

Specification of Letters Patent.

Patented Dec. 17, 1918.

1,288,152.

Application filed August 20, 1917. Serial No. 187,100.

To all whom it may concern:

Be it known that I, THOMAS F. O'SHAUGHNESSY, a citizen of the United States, and resident of New York, in the county of Bronx and State of New York, have invented certain new and useful Improvements in Piano Sounding-Boards, of which the following is a specification.

This invention relates to double sounding boards for pianos.

It is necessary that the sounding board respond to all tones throughout the compass of the instrument to produce brilliancy and quality. Heretofore these results have not been attained to a desirable degree.

The main object of my invention, therefore, is to improve the quality of tone of stringed instruments.

Another object of the invention is to provide a sounding board adapted to produce better results than heretofore has been the case.

Generally speaking these and other objects are accomplished by providing a double sounding board the air volume of which may be varied, and means for varying the air volume.

The invention is illustrated on the accompanying sheets of drawings, in which, Figure 1 is a plan view of a sounding board embodying my invention and shown in association with an equipment of bridges, strings and hammers;

Fig. 2 is a sectional view taken in the plane of line 2—2 of Fig. 1;

Fig. 3 is a rear elevation of the sounding board, a portion of the back being broken away to show a part of the internal construction;

Fig. 4 is an enlarged detail sectional view of a sounding post forming a part of my invention.

The various novel features of my invention will be apparent from the following description and drawings and will be particularly pointed out in the appended claims.

Referring particularly to the drawings, it will be seen that I have provided a piano sounding board 10 mounted in a suitable support 9. Mounted upon one surface of the sounding board are suitable bridges 11 and 12, across which are strung suitable strings 13. In this case the strings are arranged to be struck by hammers 14 for setting the strings in vibration.

The sounding board comprises a hollow

box completely closed at the margins and having a top 15, preferably of spruce wood, and a back 16, preferably of maple wood. The top 15 and back 16 are substantially parallel to and spaced from each other by a rim member 17 whereby an air chamber 18 is formed. Arranged on opposite sides of the bridge 11 are F openings 19 which are arranged in pairs. The F openings of each pair are alike in size, and the size of the openings of the pairs differs along the length of the bridge. The number of openings may be increased or decreased according to the size of the board. The forms of these openings may be varied. The large F openings are arranged at the base end of the instrument, and the small openings are arranged at the treble end of the instrument, the intermediate ones being properly graduated.

Strips 20, preferably of maple, are arranged on the under side of the top 15 for coöperation with sound posts to be mentioned later. Likewise strips 21 of the same character, which like the other strips 20 run longitudinally of the box, are mounted on the inside of the back 16. I have provided sound posts 22 which are preferably in the form of bolts and which are threaded through the back 16 and through the strips 21 and bear against the under side of the strips 20 secured to the under side of the top 15. The sound posts are adjustable lengthwise, are carried by the back and operatively press against the top 15 or sounding board proper. If the screw sound posts are screwed into the box to a greater extent than shown in Fig. 2, the top 15 and back 16 will be separated from each other an increased amount, or in other words, the air volume of the box will be increased. Likewise the air volume of the box may be decreased by withdrawing the screw sound posts a given amount.

By use of the sound posts 22 and their associated parts I have improved the quality of tone. When the sound posts have been adjusted to the desired positions for accomplishing the desired results said sound posts are locked in such positions by lock nuts 23, which are mounted on the sound posts and engage with the under side of the back 16 of the box. These sound posts 22, which are adjustable from the outside of the box, are arranged under the bridges 11 and 12 and not only sustain the pressure of the strings on the bridges, but being made in

the form of wooden screws or bolts vary the stress of the top and back of the box. These sound posts also are effective in increasing or decreasing the air volume of the sounding board to unify the pitch of the same with the pitch of the strings.

By means of my sounding board, including the adjustable sound posts, all of the tones throughout the whole compass of the instrument will be properly responded to, the sound waves occasioned by vibration of the strings thereby producing tones of brilliancy and improved quality.

It is evident that there may be various modifications of the invention herein particularly shown and described, and it is my intention to cover all such modifications which do not involve a departure from the spirit and scope of the invention as set forth in the following claims.

I claim:

1. A piano sounding board comprising a hollow box completely closed at the margins and having a sounding board and a back substantially parallel thereto, a bridge on

said sounding board, and a sound post adjustable lengthwise through the back, said sound post carried by said back and operatively pressing against the sounding board for varying the volume of the sounding box, the sounding board being ribless and having a plurality of openings arranged in proximity to said bridge.

2. A piano sounding board comprising a hollow box completely closed at the margins and having a sounding board and a back substantially parallel thereto, and a sound post adjustable lengthwise through the back, said sound post carried by said back and operatively pressing against the sounding board for varying the volume of the sounding box, the sounding board being ribless and having a plurality of openings, the sound post being adjustable from outside the box.

Signed at the city of New York, Bronx Co., State of New York, this 13th day of August, A. D. 1917.

THOMAS F. O'SHAUGHNESSY.
